VARIABLE PHASE SHIFTER

Wendell C. Morrison, Princeton, N. J., assignor
to Radio Corporation of America, a corpora-
tion of Delaware

Application June 13, 1946, Serial No. 676,549

3 Claims. (Cl. 332—27)

1

This invention relates to phase shifting devices such as are adapted to vary the phase relation between an applied alternating potential input and a delivered alternating potential output or to phase modulate an output signal.

Many different types of devices have been provided or proposed for controlling and changing the phase relation between an input potential and an output potential. Such devices have involved control elements which are more or less complicated depending on the type of device involved. Insofar as is known none of these control elements have been such as to involve nothing more than variation of the bias potential applied to an electron discharge device. This result is achieved by the present invention.

In accordance with the present invention, this result is produced by means of an electron discharge device of the heptode or pentagrid converter type. Such a device includes a cathode, an anode, a first control grid, a second control grid, a screen or shield grid which functions to shield the second control grid from the other electrodes of the device, and a suppressor grid which functions to retard the flight of secondary electrons and reflect them back to the anode. Such an electron discharge device is normally used to perform the functions of an oscillator, a mixer, and an amplifier. The present invention involves certain modifications in its input and output connections whereby it may be made to shift the phase of its output potential through an angle of 180 degrees with respect to its input potential or to phase modulate a carrier wave.

Thus (1) the input potential superimposed on a unidirectional bias potential of relatively small value is applied to the first control grid, (2) the second control grid has applied to it either a modulating frequency with suitable bias or a unidirectional bias potential which is varied from zero to a predetermined negative value, and (3) positive potential is applied through separate resistors to the anode and screen grid. When the second control grid has applied to it only such variable bias potential, it functions to shift the output current from the electron discharge device so that the input and output potentials (1) are in phase when the bias potential is zero, and (2) are 180 degrees out of phase when the bias potential has its maximum negative value.

By connecting a capacitor between the cathode and screen grid of the heptode, there is produced in its anode or output circuit a potential which may be varied in phase over a range approaching 180 degrees as a limit.

2

When a modulating frequency is superimposed on the unidirectional bias potential of its second grid, the heptode functions as a phase modulator.

Important objects of the invention are to provide an improved phase shifting device, to provide an improved phase modulator, and to provide a type of circuit whereby the usefulness of the type of electron discharge device under consideration is extended into new fields.

10 The invention will be better understood from the following description considered in connection with the accompanying drawings and its scope is indicated by the appended claims.

Referring to the drawings:

15 Figure 1 is a wiring diagram of a phase shifting device which functions to produce an output potential which is of variable amplitude and is either in phase or 180° out of phase with its input potential.

20 Figure 2 is a wiring diagram of a device which operates to gradually vary the phase relation between its input and output potentials, and

Figure 3 illustrates the device of Figure 2 as modified to operate as a phase modulator.

25 The device of Figure 1 includes a heptode 10 (6SA7 for example) which has a cathode 11, a first control grid 12, a screen grid 13, a second control grid 14, a suppressor grid 15 and an anode 16.

30 A unidirectional operating voltage for the tube 10 is applied to the anode 16 and the screen grid 13 from a source (not shown) through a terminal designated "+250 v." and through a 10,000 ohm resistor 16 and a 15,000 ohm resistor 17, respectively. The suppressor grid 15 is connected to the cathode 11 which is grounded. Bias potential is applied to the first control grid 12 from a 4.5 v. source 18 through a resistor 19. This resistor 19 is connected in series with the secondary winding 20 of a transformer having a primary winding 21 to which an alternating potential may be applied through the input terminals 22—23 of the phase shifting device. Potential for controlling the phase relation between the alternating

40 potential applied to the terminals 22—23 and that delivered through a capacitor 24 to the output terminals 25—26 is applied to the second control grid 14 from a resistor 27 which is connected in parallel with a 7.5 v. source 28 and is grounded (hence, connected to the cathode 11) at its most positive terminal.

45 It is apparent that the voltage applied to the first control grid 12 includes a unidirectional component derived from the source 18 and an alternating component derived from the second-

ary winding 20 and that the value of the alternating component E_s may be adjusted by a movable contact 29 of the resistor 19. The phase shifting control voltage E_c likewise may be varied in value by moving the contact 30 of the resistor 27.

While the theory of operation of the phase shifting device of Figure 1 is somewhat uncertain, it is now believed that the tube 10 acts as an amplifier when the control voltage E_c is near zero. Under this condition, the alternating voltage developed across the resistor 16 is 180° out of phase with the input signal E_s . The voltage developed across the resistor 17 is in phase with that across the resistor 16 and produces degeneration for the reason that the screen grid 13 lies in the electron stream. Thus the resistor 17 has a relatively large signal voltage across it which is 180° out of phase with the voltage E_s and is applied to that part of the grid 13 which lies between the grids 14 and 15.

As the control voltage E_c is made more negative, more electrons travel to that part of the grid 13 which lies between the grids 12 and 14 (lowering the screen grid voltage) and fewer electrons travel to the anode 16 (raising the anode voltage). At some particular value of E_c , the modulation of the cathode-to-anode electron stream by the signal E_s on the grid 12 is equal to the modulation by the signal on that part of the grid 13 between the grids 14 and 15. Since these two grid signals are 180° out of phase with one another, the net result is no signal in the anode circuit.

As E_c is further increased in a negative direction, the signal on screen grid 13 continues to increase and the voltage of the anode 16 continues to rise. The result might be considered as a virtual cathode existing between the grid 14 and the part of the grid 13 between the grids 14 and 15, which is partially modulated by the signal on grid 12 but is modulated much more by the large signal on the part of grid 13 between the grids 14 and 15. The resulting signal across the resistor 16 is 180° out of phase with the signal on the upper part of the grid 13 and the anode voltage now is in phase with E_s .

If E_s has a value of about 0.05 volt r. m. s. and E_c is varied from zero to -6 volts, the output voltage between the terminals 25 and 26 is shifted 180 degrees. This output voltage has a value of about three volts peak-to-peak when the terminal 30 is connected to the grounded side of the resistor 27. As the terminal 30 is made more negative, the output voltage decreases in value to approximately zero and then increases to a value of about three volts peak-to-peak.

The phase shifter of Figure 2 differs from that of Figure 1 in that (1) a capacitor 31 is connected between the screen grid 13 and cathode 11 of the device 10, and (2) bias voltage is applied to the grids 12 and 14 from a common battery 36 and resistor 32. The provision of the capacitor 31 makes it possible to shift the phase of the output voltage E_o gradually over a phase angle which approaches 180° .

As previously indicated the alternating voltage on the anode 16 is the resultant of two separate modulations of the cathode-to-anode electron stream. Thus the signal E_s on the grid 12 of Figure 2 modulates the electrons emitted from the cathode 11. This not only produces a signal in the anode circuit but also a signal in the circuit of the screen grid 13. The signal on the grid 13 is shifted in phase from the signal on the

anode 16 by the capacitor 31 in conjunction with the screen grid-to-cathode impedance.

When the control voltage E_c is near zero, the anode voltage E_o is approximately 180° out of phase with the voltage E_s . The discrepancy is caused by a small amount of modulation introduced by the out-of-phase signal on the screen grid 13. As the control voltage E_c is made more negative, more electrons go to the grid 13 thus increasing the amplitude of the signal on both parts of the grid 13. Thus the anode signal is modulated more and more by the screen grid signal as E_c is made more negative. By a suitable choice of the capacitor 31, the phase of the screen grid signal may be made so that the phase shift of the output voltage E_o approaches 180° as a limit. Increased limit of phase shift is realized at the expense of constant output amplitude. It has been found that a phase shift range of about 120° may be obtained with an amplitude variation of about 6 db.

Figure 3 shows the circuit as rearranged to function as a phase modulator. Thus the resistor 16 of Figures 1 and 2 is replaced by an anode load impedance 33, a modulating frequency f_2 is applied to the grid 14 through a transformer 34, and bias potential is applied to the grid 14 from a source shown as a battery 35.

A carrier wave f_1 is applied to the grid 12 through the transformer 20-21 and bias potential is applied to this grid from a source 18. The output voltage E_o in this case is a wave which has its phase modulated in accordance with the amplitude of the modulating frequency f_2 .

The invention thus provides a simple and reliable phase shifting or phase modulating device which is of relatively light construction, involves only a single electron discharge device and is readily operated by the variation of a single control grid potential.

I claim as my invention:

1. The combination of an electron discharge device including a cathode and anode, a screen grid and first and second control grids, a terminal adapted to be connected to a unidirectional voltage source, an impedance connected between said terminal and said anode, a resistor connected between said terminal and said screen grid, a capacitor connected between said screen grid and said cathode, and a circuit connecting said second control grid to said cathode, said circuit comprising (1) a unidirectional voltage source having a positive terminal connected to said cathode, and (2) a resistor connected in parallel with said voltage source and having a movable contact connected to said second control grid.

2. An alternating voltage phase shifter comprising an electron discharge device including a cathode and anode, a screen grid and first and second control grids, a terminal adapted to be connected to a unidirectional voltage source, a first resistor connected between said terminal and said anode, a second resistor connected between said terminal and said screen grid, a capacitor connected between said screen grid and said cathode, means for applying an alternating input potential to said first control grid, and a circuit connecting said second control grid to said cathode, said circuit comprising a variable unidirectional voltage source.

3. The combination of an electron discharge device including a cathode and anode, a screen grid and first and second control grids, a terminal adapted to be connected to a unidirectional voltage source,

tional voltage source, a load impedance connected between said anode and said terminal, an un bypassed resistor connecting said screen grid to said terminal, a capacitor connected from said cathode to the junction point of said resistor and said screen grid, means for applying an alternating input potential to said first control grid, and means for applying to said second control grid a variable magnitude negative unidirectional potential to vary the phase relation between the voltages at said first control grid and said anode.
